UNITED STATES PATENT OFFICE.

MELL A. BOLTON, OF DETROIT, MICHIGAN.

INTERNAL-COMBUSTION ENGINE.

1,250,950.

Specification of Letters Patent. Patented Dec. 25, 1917.

Application filed May 12, 1916. Serial No. 97,187.

To all whom it may concern:

Be it known that I, MELL A. BOLTON, citizen of the United States, residing at Detroit, county of Wayne, State of Michigan, have invented a certain new and useful Improvement in Internal-Combustion Engines, and declare the following to be a full, clear, and exact description of the same, such as will enable others skilled in the art to which it pertains to make and use the same, reference being had to the accompanying drawings, which form a part of this specification.

My invention relates to internal combustion engines and the object of my improvements is to provide an improved engine of the internal combustion type and they contemplate an engine in which the fuel is ignited by the heat of the charge and a working stroke occurs in the cylinder at each revolution of the shaft. In the application shown it is intended that a heavy hydrocarbon shall be used for fuel. The charge may however be ignited in any desired or known way.

I accomplish this object in the device illustrated in the accompanying drawings in which:

Figure 1 is a cross section axially through the working cylinder and two auxiliary cylinders of an engine embodying my invention.

Fig. 2 is a cross sectional detail of the working piston and adjacent parts.

Fig. 3 is an inverted plan view of the piston shown in section in Fig. 2.

Fig. 4 is a cross section, in plan, taken on the line E—E Fig. 1.

Figs. 5, 6, 7 and 8 are diagrams showing the different positions of the working part of the engine.

a is the crank case. b, c and d are cylinders extending radially from the crank case at the top thereof and having respectively pistons b², c² and d² therein connected through connecting rods b³, c³ and d³ to the wrist pin connected with the crank shaft of the engine.

a² is the oil well extending beneath the crank shaft of the engine. a³ indicates the curved bottom walls of oil pans located just above the oil well a² and provided with side walls a⁵, said walls having their upper edges in a common level, and bordering an opening connecting with the oil well a².

e⁵ indicates the wrist pins. Each of these

is formed with a cylindrical co-axial bore or cavity e⁶. e⁷ indicates apertures extending radially through the outer portion of the wall of each of the wrist pins e⁵, and forming a communication between the cavity and said pin and its exterior or bearing surface. e⁸ is a tube curved as indicated in Fig. 1, so that its outer ends extend in the direction in which the crank is turned and the opening is in a plane at right angles to its line of motion. The tube e⁸ extends from the wrist pin to a point such that it shall dip into an oil pan a³ a⁵ near the bottom thereof and thus act to scoop up a portion of the oil in said pan and convey it to the cavity a⁶ from which it shall be gradually forced to the bearing surface of the wrist pin through the apertures e⁷ by centrifugal force.

In Fig. 1 the working cylinder c is arranged vertically above the crank shaft e e². The cylinder b through which air is forced into the cylinder c as hereinafter described is shown as branching to the right of the working cylinder and the cylinder d through which an inflammable mixture is forced into the working cylinder is shown as branching to the left of the latter.

b⁴ is an aperture or series of apertures in one plane at right angles to the axis of the cylinder b through the wall thereof located so that the piston b² shall cover said apertures except at the lower end of the stroke of said piston at which point the apertures are uncovered to admit air therethrough to supply the vacuum formed in the cylinder b by the descent of the piston b², in a method well understood in the art. b⁵ is an intake pipe communicating with the apertures b⁴ and provided with a throttle valve b⁶.

c⁴ c⁵ are apertures formed through the walls of the cylinders c³ at such a position that they shall be uncovered at the lower end of the stroke of the working piston c² to discharge the products of combustion. c⁶ c⁷ are the exhaust passages communicating with the apertures c⁴.

d⁴ d⁵ and d⁶ are the apertures, intake passage and throttle valve appurtenant to the cylinder d and entirely analogous to those described in connection with the cylinder b.

d⁷ is a carbureter or means for supplying fuel to the air being drawn into the cylinder d. b⁸ is a passage leading from the upper

end of the cylinder b to the upper end of the cylinder c . b^9 is a puppet valve opening from the passage b^8 .

d^8 is a passage communicating with the upper end of the cylinder d and the upper end of the cylinder c . d^9 is a puppet valve in the passage d^8 opening toward the cylinder c .

c^8 is a passage communicating with the outer air and adapted to be put into communication with the cylinder c for the purpose hereinafter described. c^9 is a puppet valve in the passage c^8 opening toward the cylinder c .

15 The outer ends of the connecting rods b^3 d^3 are formed in the shape of spheres, or balls, as shown in dotted lines in Fig. 1 and indicated in the cross section of Fig. 2. These balls fit in sockets c^{11} in the cylinder 20 and are held in place by a split ring c^{12} and an engaging ring c^{13} fitting over a ball on the split ring c^{12} and being confined by the lag-screw c^{14} . c^{15} are conduits or passages leading from a groove in the periphery of 25 the piston radially inward and communicating with the bearing surface of the socket c^{11} .

30 f is a yoke pivotally secured upon the wrist pin e^6 . The connecting rod c^8 (Fig. 1) is rigidly secured in the yoke f with its axis intersecting the axis of the wrist pin. There are lugs f^2 f^3 on each side of the yoke f at the top thereof adjacent to and on opposite sides of the point at which the connecting rod c^8 is fastened to said yoke. The 35 inner end of the connecting rod b^8 is pivoted to the lug f^2 and the inner end of the connecting rod d^8 is pivoted to the lug f^3 .

The engine so far as its cycle is concerned operates as follows:

40 If we consider that there is a compressed and ignited charge in the cylinder c above the piston c^2 and the crank is turning in the direction indicated by the arrows in Fig. 1, the piston c^2 descends imparting the force of 45 the charge above it to the crank shaft and the pistons b^2 and d^2 are drawn inward. When the piston c^2 passes over the aperture c^4 the exhaust takes place, the gases being driven out through the exhaust pipe c^5 , and 50 because of their inertia drawing a slight vacuum in said cylinder which is supplied by fresh air from the passage c^8 , the valve c^8 being drawn from its seat by the suction due to the inertia of the discharged 55 exhaust gases. The pistons b^2 d^2 are drawn inward producing a partial vacuum above them until they pass respectively the apertures b^4 and d^4 when air rushes in through the intake pipe b^6 and a combustible mixture 60 through the intake pipe d^6 to supply the vacuum in their respective cylinders.

Upon the further turning of the crank shaft, the piston b^2 begins to ascend covering the apertures b^4 the piston c^2 covering the aperture c^4 and the piston d^2 covering the

aperture d^4 and each of said pistons compressing the gases above it. Owing to the position of the cylinder b and the point of attachment of its connecting rod to the crank, such piston is a little in advance of 70 the piston c^2 and for a similar reason the piston d^2 is a little behind the piston c^2 . The charge of air above the piston b^2 will be forced through the pipe b^8 , past the valve b^9 , into the cylinder c above its piston 75 c^2 , and the gases above the last named piston will be highly compressed and thereby heated to a high temperature. The inflammable mixture will now be forced in from the cylinder d into the cylinder c above its 80 piston c^2 and will be ignited as it enters thus heating the charge in the cylinder c and raising the pressure above the piston c^2 which then descends on its working stroke as before described. 85

The above cycles are illustrated diagrammatically in Figs. 6 to 8 inclusive. In Fig. 5 the working stroke has just commenced. In Fig. 6 the exhaust from the cylinder c has taken place and the air is being supplied to 90 the cylinder b . In Fig. 7 compression has commenced in the cylinder b and in Fig. 8 the air charge has just been transferred from the cylinder b to the cylinder c and the charge of explosive mixture which has already been considerably compressed is being forced into the cylinder above the piston c^2 . 95

To facilitate the discharge of the exhaust gases I employ the construction shown most distinctly in Fig. 4 in which c^5 c^{5a} are exhaust manifolds or pipes from which, respectively, lead discharge pipes g^4 and g^5 . The pipes g^4 have adjacent openings into an enlargement g^6 from which leads a discharge passage g^6 . By this arrangement an 100 injecting action is secured. By one of the pipes g^3 or g^4 discharging its gas draws a vacuum in the other of said pipes and facilitates the discharge of the gases therethrough. 110

As the ports d^4 are opened suddenly there is a quick strong inrush of air which serves to efficiently spray a heavy hydrocarbon liquid. When a separate cylinder is used as a 115 pump the clearance may be small and the in-draft is especially strong.

What I claim is:

1. In an internal combustion engine, the combination of a working cylinder and piston therein, said piston being adapted to 120 compress a charge of gas above it in said cylinder, a second cylinder and piston therein, and means whereby the movement of the piston in said second cylinder shall draw in a charge of combustible gas and 125 force it into said working cylinder during the compression of the latter.

2. In an internal combustion engine, the combination of a working cylinder and piston therein, said piston being adapted to 130

compress a charge of gas above it in said cylinder, a second cylinder and piston therein, and means whereby the movement of the piston in said second cylinder shall 5 draw in a charge of combustible gas and force it into said working cylinder during the compression of the latter, a third cylinder, means whereby said third cylinder draws in a charge of air and compresses the 10 same and forces it into said working cylinder during the compression of the latter.

3. In an internal combustion engine, the combination of a working cylinder and piston therein, said piston being adapted to 15 compress a charge of gas above it in said cylinder, a second cylinder and piston therein, and means whereby the movement of the piston in said second cylinder shall draw in a charge of combustible gas and 20 force it into said working cylinder during the compression of the latter, a third cylinder, means whereby said third cylinder draws in a charge of air and compresses the 25 same and forces it into said working cylinder during the compression of the latter, the discharge from said third cylinder into the working cylinder occurring before the discharge from said second cylinder to said working cylinder.

30 4. In an internal combustion engine, the combination of a crank shaft, a working cylinder extending radially to said shaft, a piston in said working cylinder, a crank on said shaft, said piston being united by a 35 connecting rod to said crank, a cylinder located upon each side of said working cylinder and extending radially to said shaft, pistons in each of the last named cylinders having connecting rods joined to said crank, 40 means for supplying a combustible gas to one of said cylinders and air to the other of said cylinders, the cylinder to which the combustible gas is supplied being on the side of the working cylinder from which the 45 crank moves in its rotation and the cylinder to which air is supplied being upon the side of said working cylinder toward which the crank moves in its rotation.

5. In an internal combustion engine, the 50 combination of a crank shaft, a working cylinder extending radially to said shaft, a piston in said working cylinder, a crank on said shaft, said piston being united by a connecting rod to said crank, a cylinder located upon each side of said working cylinder and extending radially to said shaft, pistons in each of the last named cylinders having connecting rods joined to said crank, 55 means for supplying a combustible gas to one of said cylinders and air to the other of said cylinders, the cylinder to which the combustible gas is supplied being on the side of the working cylinder from which the crank moves in its rotation and the cylinder 60 to which air is supplied being upon the side

of said working cylinder toward which the crank moves in its rotation, apertures in the walls of said cylinders adapted to be uncovered by the pistons in the outer ends of their strokes for the purpose described. 70

6. In an internal combustion engine, the combination of a crank shaft, a working cylinder extending radially to said shaft, a piston in said working cylinder, a crank on said shaft, said piston being united by a connecting rod to said crank, a cylinder located upon each side of said working cylinder and extending radially to said shaft, pistons in each of the last named cylinders having connecting rods joined to said crank, means for 80 supplying a combustible gas to one of said cylinders and air to the other of said cylinders, the cylinder to which the combustible gas is supplied being on the side of the working cylinder from which the crank moves in its rotation and the cylinder to which air is supplied being upon the side of said working cylinder toward which the crank moves in its rotation, a passage communicating with the outer air and leading to 85 said working cylinder and an inwardly opening automatic valve in said passage. 90

7. In an internal combustion engine, the combination of a crank shaft, a working cylinder extending radially to said shaft, a piston in said working cylinder, a crank on said shaft, said piston being united by a connecting rod to said crank, a cylinder located upon each side of said working cylinder and extending radially to said shaft, pistons in 100 each of the last named cylinders having connecting rods joined to said crank, means for supplying a combustible gas to one of said cylinders and air to the other of said cylinders, the cylinder to which the combustible gas is supplied being on the side of the working cylinder from which the crank moves in its rotation and the cylinder to which air is supplied being upon the other side of said working cylinder toward which 105 the crank moves in its rotation, apertures in the walls of said cylinders adapted to be uncovered by the pistons in the outer ends of the strokes, a yoke in said crank, the working piston being rigidly secured to said yoke 110 and the pistons in the other cylinders being secured to lugs on opposite sides of said yoke. 115

8. The combination of a working cylinder and a piston adapted to reciprocate therein, an auxiliary cylinder having its end closed so as to secure a minimum clearance, an intake port to said auxiliary cylinder, and means for opening said intake port at the outer end of the stroke of said piston, a carburetor connecting with said intake port, and means for forcing the charge in said auxiliary cylinder into the working cylinder. 120 125

9. In an internal combustion engine, the combination of a working cylinder and pis- 130

ton therein, a second cylinder and piston therein, and means whereby the movement of the piston in said second cylinder shall draw in a charge of combustible gas and force it into said working cylinder, a third cylinder, means whereby said third cylinder shall draw in a charge of air and force the same into said working cylinder.

10. In an internal combustion engine, the combination of a crank shaft, a working cylinder extending radially to said shaft, a piston in said working cylinder, a crank on said shaft, said piston being united by a connecting rod to said crank, a cylinder located upon each side of said working cylinder and extending radially to said shaft, pistons in each of the last named cylinders having connecting rods joined to said crank, means for

supplying a combustible gas to one of said cylinders and air to the other of said cylinders, the cylinder to which the combustible gas is supplied being on the side of the working cylinder from which the crank moves in its rotation and the cylinder to which air is supplied being upon the side of said working cylinder toward which the crank moves in its rotation, a delivery passage leading from each of the side cylinders to said working cylinder, a non-return valve in said passage opening toward the working cylinder, and a spring acting to hold said valve upon its seat.

In testimony whereof, I sign this specification.

MELL A. BOLTON.
